US0D1095547S

(12) **United States Design Patent** (10) Patent No.: **US D1,095,547 S**
(45) Date of Patent: ** Sep. 30, 2025

(54) **DISPLAY SCREEN OR PORTION THEREOF HAVING A GRAPHICAL USER INTERFACE**

(71) Applicant: **Zoox, Inc.**, Foster City, CA (US)

(72) Inventors: **Timothy David Kentley-Klay**,
Stanford, CA (US); **Auver Cedric Austria**, San Francisco, CA (US);
Donovan Anton Bass, San Francisco, CA (US); **Duncan John Curtis**,
Hayward, CA (US); **Michael Moshe Kohen**, Palo Alto, CA (US); **Koun Han**, San Francisco, CA (US); **Jannie Wing Sze Lai**, Berkeley, CA (US)

(73) Assignee: **Zoox, Inc.**, Foster City, CA (US)

(**) Term: **15 Years**

(21) Appl. No.: **29/829,886**

(22) Filed: **Mar. 8, 2022**

Related U.S. Application Data

(62) Division of application No. 29/662,061, filed on Aug. 31, 2018, now Pat. No. Des. 950,587.

(51) **LOC (15) Cl.** **14-04**

(52) **U.S. Cl.** **USPC** **D14/485**

(58) **Field of Classification Search**

USPC D14/485-495

CPC G06F 3/048-04897

(57) **CLAIM**

The ornamental design for a display screen or portion thereof having a graphical user interface, as shown and described.

DESCRIPTION

FIG. 1 is a view of a first embodiment of a display screen or portion thereof having a graphical user interface;

FIG. 2 is a view of a second embodiment of a display screen or portion thereof having a graphical user interface;

FIG. 3 is a view of a third embodiment of a display screen or portion thereof having a graphical user interface;

FIG. 4 is a view of a fourth embodiment of a display screen or portion thereof having a graphical user interface;

FIG. 5 is a view of a fifth embodiment of a display screen or portion thereof having a graphical user interface;

FIG. 6 is a view of a sixth embodiment of a display screen or portion thereof having a graphical user interface;

FIG. 7 is a view of a seventh embodiment of a display screen or portion thereof having a graphical user interface;

FIG. 8 is a view of an eighth embodiment of a display screen or portion thereof having a graphical user interface;

FIG. 9 is a view of a ninth embodiment of a display screen or portion thereof having a graphical user interface;

FIG. 10 is a view of a tenth embodiment of a display screen or portion thereof having a graphical user interface;

FIG. 11 is a view of an eleventh embodiment of a display screen or portion thereof having a graphical user interface; and,

FIG. 12 is a view of a twelfth embodiment of a display screen or portion thereof having a graphical user interface. The black dot-dashed broken lines depict the display screen or portion thereof and form no part of the claimed design.

The white dot-dashed broken lines depict a boundary of the claimed design. The white dot-dashed broken lines and the contents within form no part of the claimed design. The dashed broken lines depict portions of the display screen or portion thereof having a graphical user interface that form no part of the claimed design.
